UNITED STATES PATENT OFFICE

LEONARD J. FOX, OF CINCINNATI, OHIO

DESIGN FOR AN AUTOMOBILE HOOD

Application filed April 2, 1930. Serial No. 35,105. Term of patent 14 years.

To all whom it may concern:

Be it known that I, LEONARD J. FOX, a citizen of the United States, residing at Cincinnati, in the county of Hamilton and State of Ohio, have invented a new, original, and ornamental Design for Automobile Hood, of which the following is a specification, reference being made to the accompanying drawings, forming a part thereof.

Fig. 1 is a perspective view of an automobile hood showing the new design.

Fig. 2 is an enlarged detail view in perspective of one of the hinges of the hood design.

I claim:

The ornamental design for an automobile hood as shown.

In testimony whereof I affix my signature.

LEONARD J. FOX.
